UNITED STATES PATENT OFFICE.

GOTTFRIED WEGELIN, OF KALSCHEUREN, GERMANY.

APPARATUS FOR MANUFACTURING LAMPBLACK.

SPECIFICATION forming part of Letters Patent No. 664,916, dated January 1, 1901.

Application filed February 10, 1900. Serial No. 4,777. (No model.)

To all whom it may concern:

Be it known that I, GOTTFRIED WEGELIN, a subject of the King of Prussia, Emperor of Germany, residing at Kalscheuren, in the 5 Kingdom of Prussia, Germany, have invented certain new and useful Improvements in Apparatus for the Manufacture of Lampblack, (for which I have applied for patent in Germany, dated October 28, 1899,) of which the 10 following is a specification.

Hitherto the heat evolved in the production of lampblack from tar distillates has either been allowed to go to waste or has in exceptional cases been used for heating purposes 15 of inconsiderable importance, and for the production of the distillate itself a special furnace has been used. The working costs of the two separated processes were correspondingly proportioned.

20 The object of the present invention is to so combine the existing apparatus for producing lampblack from tar distillates with any desired construction of apparatus for distilling tar that the heat evolved in preparing the lampblack in the former is used for heating the latter, whereby, in the first place, one of the furnaces hitherto employed is rendered unnecessary, and, in the second place, the two distinct operations, which are, first, the 25 distilling of tar, and, secondly, the manufacture of lampblack, are combined to form a comparatively simple one.

As shown on the accompanying drawing, in which two forms of construction—viz., a vertical and a horizontal distilling apparatus—35 are shown in section, the vessel A containing the tar distillate is so arranged underneath or at the front of the distilling apparatus D

that the flames leaping out of the first play as evenly as possible on the latter before passing 40 into the back chamber K, where the lampblack is deposited. The carburet of hydrogen evolved from the distilling apparatus D can be led off and condensed in the usual manner.

Apart from the advantages already mentioned the combination of a distilling apparatus and apparatus for making lampblack has the special advantage that the operation 45 can take place continuously and automatically. For the purpose of attaining this end 50 it is only necessary to conduct the vapors entirely or in part from the distilling apparatus D after being condensed into the vessel A to be burned. By this arrangement all delay in the operation is avoided.

55 What I claim, and desire to secure by Letters Patent of the United States, is—

In combination in combined apparatus for producing lampblack and apparatus for the distillation of tar, the combination of a tar-distilling chamber, a furnace beneath it, and a lampblack-settling chamber, in communication with the said furnace, whereby the heat from the furnace may distil the tar in the said distilling-chamber, and some of the combustible products therefrom may be selected 60 and utilized in the said furnace without combustion of the other distillation products, substantially as set forth.

In testimony whereof I have hereunto set 70 my hand in the presence of two witnesses.

GOTTFRIED WEGELIN.
